US0D1111985S

(12) **United States Design Patent** (10) **Patent No.:** **US D1,111,985 S**
(45) **Date of Patent:** **** Feb. 10, 2026**

(54) **CAR MAT**

(71) Applicant: **Taizhou Yusen Auto Accessories Co., Ltd.**, Wenling (CN)

(72) Inventor: **Fanggen Chen**, Wenling (CN)

(73) Assignee: **Taizhou Yusen Auto Accessories Co., Ltd.**, Wenling (CN)

(**) Term: **15 Years**

(21) Appl. No.: **29/971,841**

(22) Filed: **Nov. 6, 2024**

(51) LOC (15) Cl. **12-16**

(52) U.S. Cl.

USPC **D12/203**

(57) **CLAIM**

The ornamental design for a car mat, as shown and described.

DESCRIPTION

FIG. 1 is a perspective view of my new design, showing a car mat;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged partial view of a part enclosed 9 in FIG. 5.

The line shading in FIGS. 1-9 represents contour and not surface ornamentation.

The broken lines shown in the figures illustrate environmental or other features that form no part of the claimed design.

1 Claim, 9 Drawing Sheets
